UNITED STATES PATENT OFFICE

96,432

DESIGN FOR A VELOCIPED

Harold L. van Doren and John G. Rideout, Toledo,
Ohio, assignors to The American-National
Company, Toledo, Ohio, a corporation of Ohio

Application April 27, 1935, Serial No. 56,606

Term of patent 3½ years

To all whom it may concern:

Be it known that we, Harold L. van Doren and John G. Rideout, both citizens of the United States of America, residing at Toledo, in the county of Lucas in the State of Ohio, have invented a new, original, and ornamental Design for a Velocipede, of which the following is a specification, reference being had therein to the accompanying drawing, forming a part thereof, wherein:

Figures 1 and 2 are perspective views of our velocipede.

We claim:

The ornamental design for a velocipede substantially as shown.

HAROLD L. VAN DOREN.
JOHN G. RIDEOUT.
